UNITED STATES PATENT OFFICE.

JOHN ELLIS, OF LYNN, MASSACHUSETTS.

DESIGN FOR A LIQUID-FILTER CASE.

SPECIFICATION forming part of Design No. 26,029, dated September 15, 1896.

Application filed January 16, 1895. Serial No. 535,154. Term of patent 7 years.

To all whom it may concern:

Be it known that I, JOHN ELLIS, a citizen of the United States, residing at Lynn, in the county of Essex and State of Massachusetts, 5 have invented and produced a new and original Design for a Liquid-Filter Case, of which the following is a specification, reference being had to the accompanying drawings, showing the same.

10 This design relates to filter-cases intended more especially for use in filtering water, and is shown in the accompanying sheet of drawings, in which the figure represents in perspective a liquid-filter case.

15 The case is substantially in the form of a

tube, its central body portion A is in a straight longitudinal line, and above and below this straight-line portion its surface is raised or projects, forming a band B, which has a roughened appearance, and from each band 20 it extends in a curved or hollow line, as shown, to each end C.

Having thus described my design for liquid-filters, what I claim is—

The design for a liquid-filter case herein 25 shown and described.

JOHN ELLIS.
